UNITED STATES PATENT OFFICE.

FREDERICK H. RASCHER, JR., OF ARLINGTON HEIGHTS, ILLINOIS.

PAINTBRUSH.

Application filed June 9, 1923. Serial No. 344,354.

To all whom it may concern:

Be it known that I, FREDERICK H. RASCHER, Jr., a citizen of the United States, residing at Arlington Heights, in the county of Cook and State of Illinois, have invented a certain new and useful Improvement in a Paintbrush, of which the following is a specification.

My invention relates to improvements in 10 detachable brush handles.

An important object of the invention is to provide a handle which can be easily and firmly attached to many styles of brushes.

Another object of the invention is to provide 15 a durable and convenient handle which can be used with a number of sets of bristles.

Another object of the invention is to provide holding means for brushes which will be stronger and of better construction than 20 the usual equipment thereof.

Other objects and advantages of this invention will be apparent during the course of the following description.

In the accompanying drawings forming 25 a part of this specification and in which like numerals are employed to designate like parts throughout the same:

Figure 1 is a side elevation of an assembled brush,

Figure 2 is a sectional view taken on line 2-2 of Figure 1,

Figure 3 is a longitudinal vertical section, through the center of the brush,

Figure 4 is a partial end view of the 35 brush,

Figure 5 is a sectional view taken on line 5-5 of Figure 3,

Figure 6 is a perspective view of the brush casing,

Figure 7 is a plan view of the assembled brush, and

Figure 8 is a plan view of one of the details.

In the drawings, wherein for the purpose 45 of illustration is shown the preferred embodiment of my invention, the numeral 10 designates a casing which receives a brush head 11, the sides being provided with indentations 12 for retaining the brush head 11 within the casing. The top of the casing has a semi-circular ridge 13 formed thereon and is provided with end apertures 14, and a central opening 15.

A threaded sleeve 16, provided with a 55 transverse bore 17, is adapted to fit into the

opening 15. Fitting slidably through the ridge 13 and the sleeve 16 is a connecting pin 18. The numeral 19 generally denotes the handle which is preferable constructed of aluminum or other like metal, although 60 wood or composition may be used satisfactorily. The lower part of the handle 19 is supported by a base member 20 which has a groove 21 formed therein for receiving the ridge 13. The upper portion of the handle 65 assumes the usual hand gripping member 22, the extreme end 23 being made solid in order to reinforce the structure.

24 is the fastening rod, the upper end 25 of which is flattened and has a collar 26 70 rigidly secured thereto, a slight distance below the end in order to permit the locking key 27 to be positioned thereon. The lower end of the fastening rod 24 is screw threaded as at 28 and is adapted to fit the sleeve 75 16.

In order to separate the brush members, the key 27 is fitted over the flattened end 25 of the rod 24 and turned, whereupon the 80 sleeve 16 will permit the removal of the connecting pin 18. The casing 10 is detached from the handle 19, and the brush head 11 extracted. It is to be noted when the brush is fully assembled, the side walls of the casing 10 having the indentations 12 85 therein will be held close against the brush head 11 due to the pin 18 engaging and drawing the center of the top wall of the casing 10 upwardly, and when the casing 10 is removed from the handle the side 90 walls of the casing will permit the head 11 to be removed therefrom. A new brush can then be forced into the casing 10 and the device assembled and used again.

It is to be understood that the form of 95 my invention herewith shown and described is to be taken as a preferred example of the same, and that various changes in the size, shape, and arrangement of parts may be resorted to without departing from the 100 spirit of my invention or the scope of the subjoined claims.

Having thus described my invention, I 105 claim:

1. In a device of the character described, 110 comprising a brush casing, a brush head having bristles therein secured in the casing, a handle member, a threaded sleeve having a transverse bore therein, a pin connecting the sleeve and casing, a fastening

- rod having one end threadedly fastening the casing to the said handle member, and means for turning the fastening rod.
2. In a device of the character described comprising a brush casing, a brush head provided with bristles secured in the casing, a handle member, a threaded sleeve, a pin hingedly connecting the sleeve with the casing, a fastening member having one end 10 threaded and fitting into the sleeve and the other end provided with a collar for fastening the casing and handle member, and means to permit turning of the fastening rod.
- 15 3. In a device of the character described comprising a brush casing, a ridge formed on the casing, and means for securing a brush head in the said casing; a brush head, bristles fastened in the brush head; a threaded sleeve having a transverse bore 20 through the lower end thereof; a pin fitting in the ridge of the casing and through the sleeve; a handle member composed of a base plate having a groove for receiving the casing ridge, and a gripping member 25 having the upper extremity partially solid with a circular recess formed therein; a fastening rod having its lower end threaded and fitted into the sleeve, and the upper end flattened and provided with a collar; said flattened portion adapted to be engaged for turning the fastening rod.
- In testimony whereof, I have affixed my signature in the presence of two witnesses.
- FREDERICK H. RASCHER, JR.
